US0D1032423S

(12) **United States Design Patent** (10) Patent No.: **US D1,032,423 S**
(45) Date of Patent: ** Jun. 25, 2024

(54) **CHASSIS FOR VEHICLE WITH DIGITAL COCKPIT**

(71) Applicant: **Samsung Electronics Co., Ltd.**, Suwon-si (KR)

(72) Inventors: **Kwan-Jun Ryu**, Suwon-si (KR); **Kyung-Jin Lee**, Suwon-si (KR); **Jei-Sung Park**, Suwon-si (KR); **Ki-Byung Chai**, Suwon-si (KR)

(73) Assignee: **SAMSUNG ELECTRONICS CO., LTD.**, Suwon-si (KR)

(**) Term: **15 Years**

(21) Appl. No.: **29/797,781**

(22) Filed: **Jul. 2, 2021**

(30) **Foreign Application Priority Data**

(57) **CLAIM**

The ornamental design for a chassis for vehicle with digital cockpit, as shown and described.

DESCRIPTION

FIG. 1 is a front perspective view of a chassis for vehicle with digital cockpit showing our new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof; and,

FIG. 8 is a rear perspective view thereof.

The dashed broken lines in the drawings illustrate portions of the chassis for vehicle with digital cockpit that form no part of the claimed design.

1 Claim, 8 Drawing Sheets
